Richard H. Strickland, 132 Devonshire Road,
Wilmington, Del.

Filed July 10, 1963, Ser. No. 75,728

Term of patent 14 years

(Cl. D44—29)

Fig. 1.

Fig. 2.

Fig. 5.

Fig. 4.

FIG. 1 is a top plan view of a dough roller embodying my new design, the dominant feature of which resides in the portions shown in full lines;

FIG. 2 is an elevational view of one side thereof, the opposite side being substantially a mirror image thereof;

FIG. 3 is an end elevational view; and

FIG. 4 is a bottom plan view.

The handle portion shown in broken lines in FIG. 1 has been omitted from FIGS. 2 and 4 for convenience of illustration.

I claim:

The ornamental design for a dough roller, substantially as shown and described.
